UNITED STATES PATENT OFFICE.

BENJAMIN F. HART, JR., OF HOBOKEN, NEW JERSEY.

COOLING-TOWER.

1,228,207.

Specification of Letters Patent. Patented May 29, 1917.

Application filed March 29, 1915. Serial No. 17,788.

To all whom it may concern:

Be it known that I, BENJAMIN F. HART, Jr., a citizen of the United States, residing at Hoboken, in the county of Hudson and State of New Jersey, have invented certain new and useful Improvements in Cooling-Towers, of which the following is a specification.

My invention relates to water towers such as are set forth in my prior Patent 902,875 for cooling towers bearing date November 3, 1908, and is an improvement on such prior patent.

Furthermore the invention is an improvement over the aforesaid patent arranged to permit a more efficient distribution of such trays as are illustrated in my prior patents numbered 1,023,564 and 1,040,318 respectively.

20 The principal object of the present invention is to improve on the means for distributing the water from the delivery piping to the cooling decks whereby equal distribution is obtained and a maximum contact between the finely divided water and a maximum of cooling air.

A second object of the invention is to improve on the arrangement of cooling trays whereby the trays are arranged in sets having double decks with the trays of the upper deck being in staggered relation to the trays of the lower deck in each set, whereby more efficiently to distribute the water dripping down through the sets of trays so that 35 the cooling air may have more efficient access to the water.

Provision is made in my former Patent 902,875 for certain aprons or spray shields. A third object of the invention is to improve 40 the construction of these aprons or spray shields so that the supporting frames for these spray shields may be arranged to act as trusses for the main tower.

Furthermore, I have found in the use of my tower, as set forth in Patent 902,875 high winds interfere with the proper operation of the device and cause waste of the water. A fourth object of the invention is to improve 50 on the construction of such a tower, so that an auxiliary spray preventer in the form of a suitable baffle arrangement extends up through the center of the tower from top to bottom thereof.

A fifth object of the invention consists in 55 the provision of an improved arrangement of piping provided with special nozzles ar-

ranged to discharge jets of compressed air across the path of the descending water during the periods when there are no natural air currents, such as in a calm. 60

With the above and other objects in view as will be hereinafter set forth, the invention consists in general of certain novel details of construction and combinations of parts, hereinafter fully described, illustrated in the accompanying drawings and specifically claimed.

In the accompanying drawings like characters of reference indicate like parts in the several views, and:— 70

Figure 1 is a plan view of the tower, certain of the parts being broken away to show the parts beneath.

Fig. 2 is a vertical section on the line II—II of Fig. 1. 75

Fig. 3 is a perspective view of a portion of the compressed air pipes used herewith and the attached nozzles.

Fig. 4 is a view, partly in elevation and partly in section of one of the water delivery 80 nozzles used herewith, showing in dotted lines the relation of the trays.

Fig. 5 is a detail showing certain screen plates for the wind screens of the invention.

In carrying out the objects of the invention there is provided a suitable tower or framework which may be of any preferred cross section or plan arrangement although the frame is preferably rectangular and consists in general of uprights 10 which rest 85 upon and have secured thereto a drip pan 11. The uprights are connected by horizontal tie angles 12 upon which rest the I-beams 13, the latter being suitably fastened to the tie angles. 95

Extending above the upper I-beams are water distributing pipes 14 which are connected to a header 15 leading from a stand pipe 16, the latter receiving hot water to be cooled from a suitable source of supply 100 as the pipe 17.

Each of the pipes 14 is provided with a series of upstanding nozzles 18, each carrying a skirt or distributor cone 19, so arranged that the water flowing out of the 105 nozzles will be spread by the skirts or distributor cones into the trays 20, the latter being preferably of the type disclosed in one or the other of my Patents 1,023,564 or 1,040,318 above referred to. 110

These trays are arranged in double decked sets, each set being fixed on the upper and

lower flanges of respective horizontal rows of the I-beams 13 and the trays of the upper deck being in laterally staggered relation with the trays of the lower deck. As described in my former and herein referred to U. S. Patents Nos. 1,023,564 and 1,040,318, the water in the pans or trays overflows over the edges of the trays and passes off the supporting and diffusing ledges to the pans or trays on deck below in two distinct lines instead of one as in the case of flat boards heretofore employed. Furthermore, in the herein disclosed arrangement the water splashes clear of the sides or edges of the pans or trays and forms two more lines of drops, so that by the present disposition of pans or trays, the water is broken up into four distinct lines of drop for every tray or pan in each horizontal group of trays, and hence exposes more surface of the water to the cooling influence of the air than when flat boards are used. By this arrangement the sheets of water are so broken up that they amount in practice to a fine spray and the cooling air has access to the minute particles thus insuring rapid and efficient cooling.

The arrangement of the wind or spray shields in the present device consists of upwardly and outwardly extending supporting members 21, each having its lower end attached directly to the main frame or the drip pan, while its upper part is connected to the main frame by a tie bar 22. These members 21 are connected by horizontally disposed frames consisting of rods or pipe lengths 23 connected by couplings as turn buckles 24 so that the rods or pipe lengths 23 may be adjusted and each frame may be tightened up and constitute a truss for supporting the main frame from lateral flexure. Sheets 25 forming the spray preventer, are suitably fastened together at their vertical edges by lap joints or solder and secured to the pipe lengths 23 by means of wires 26 on all four sides of the frame work of the tower. Said wires 26 pass through the sheets 25 and reinforcing clips 27 placed on the outer side of the sheets 25, as shown in Fig. 5, the inner ends of the wires 26 are passed around the pipe lengths 23 and twisted together, thereby firmly holding the sheets 25 forming the spray preventer to the pipe sections 23 and preserving their proper angle and relation to the frame work 10 and the groups of trays 20 at each gallery section in all kinds of weather. The upper edge of each set of these sheets 25 forming the spray preventers or shields is substantially in a plane horizontal with the lower edge of the next set above, so that direct horizontal currents of air are prevented from passing across the down flowing water.

It sometimes happens that, during high winds, even such wind screens as have been

described will be ineffective, so that I prefer to erect in the longitudinal center of the device an auxiliary baffle consisting of spaced upright bars 28 to which are connected baffle plates 29 each consisting of a vertically disposed plate, the plates being arranged in staggered relation as clearly shown in Fig. 2, so that air passing through the baffle will take the courses as indicated by the arrows.

When there is no wind, or even when there is but very little wind, apparatus of this character frequently becomes defective in operation, the water not being sufficiently cooled. To overcome this defective condition, I provide on each side of the middle baffle a vertical air stand pipe 30 connected to each other by a branch pipe 34, and to which are connected headers 31 extending in opposite directions from the pipes 30 and each of said headers 31 is provided with spaced branch pipes 32 and having flaring nozzles 33 carried by the outer ends of the respective pipes 32, the nozzles on one side of the center baffle being directed inwardly and downwardly while the nozzles on the other side are directed outwardly, whereby an air current is induced from one side of the frame to the other when compressed air is forced through these nozzles 33.

There is also provided a suitable ladder 35 which leads up to an inspection gallery 36.

Thus by a simple and efficient apparatus provision is made for accomplishing all of the objects hereinbefore set forth.

What I claim is:—

1. A cooling tower comprising a supporting frame work, a series of water pans or trays arranged at different levels thereon and having means to discharge from one series to another at a lower level, and a series of vertical water distributing nozzles arranged adjacent to and over the upper water pans of the tower, each nozzle being surrounded by a water distributor cone between its outlet and the pans.

2. A cooling tower comprising a supporting frame work, a series of water pans arranged in vertically spaced layers and having lateral discharge means, the water pans in one layer being in lateral staggered relation to the water pans in the next layer and a series of vertical water distributing nozzles arranged adjacent to and over the upper water pans, each nozzle being surrounded by a water distributor cone between its outlet and the pans.

3. A cooling tower comprising a supporting frame work including sets of I-beams arranged in spaced parallel relation in horizontal planes, a series of laterally spaced water pans supported on the upper flanges of two of the beams of a set, and a second series of laterally spaced water pans sup-

ported on the lower flanges of the beams, the second series of pans being arranged in staggered relation to the first series of pans, and a series of vertical water distributing 5 nozzles arranged over the upper water pans.

4. A cooling tower comprising a supporting frame work, a series of water pans arranged at different levels thereon, a series of inclined supporting members secured to 10 the frame work and extending upwardly and outwardly about said frame work, rods engaging the supporting members and provided with devices for adjusting the tension thereof and sheets forming wind shields 15 secured to said rods.

5. A cooling tower comprising a supporting frame work, a series of water pans arranged at different levels thereon and having means to discharge from one level to 20 another, a series of inclined supporting members secured to the frame work and extending upwardly and outwardly laterally of said frame work, sheets forming wind shields secured to said inclined supporting 25 member and arranged to leave spaces substantially above and below the same through the tower, and a set of baffles intermediate the wind shields arranged to check the flow of air from one side to the other of the 30 frame work.

6. A cooling tower comprising a supporting frame work, a series of water pans arranged at different levels thereon and having means to discharge from one level to 35 another, a series of inclined supporting members secured to the frame work and extending upwardly and outwardly laterally of said frame work, sheets forming wind shields secured to said inclined supporting 40 members, and arranged to leave spaces substantially above and below the same through the tower, and a set of baffles intermediate the wind shields arranged to check the flow of air from one side to the 45 other of the frame work and comprising

spaced sets of vertically disposed plates arranged in staggered relation.

7. A cooling tower comprising a supporting frame work, a series of water pans arranged at different levels thereon and having means to discharge from one level to another, a series of inclined supporting members secured to the frame work and extending upwardly and outwardly laterally of said frame work, sheets forming wind 50 shields secured to said inclined supporting members and arranged to leave spaces substantially above and below the same through the tower, a set of baffles intermediate the wind shields arranged to check the flow of 55 air from one side to the other of the frame work, and means to induce an air current through the baffles.

8. A cooling tower comprising a supporting frame work, a series of water pans arranged at different levels thereon and having means to discharge from one level to another, a series of inclined supporting members secured to the frame work and extending upwardly and outwardly laterally of said frame work, sheets forming 60 wind shields secured to said inclined supporting members and arranged to leave spaces substantially above and below the same through the tower, a set of baffles intermediate the wind shields arranged to 65 check the flow of air from one side to the other of the frame work, and means to induce an air current through the baffles consisting of downwardly and inwardly directed blast nozzles on one side of said baffles, and outwardly directed blast nozzles on 70 the opposite side thereof, and an air supply 75 means for the nozzles.

In testimony whereof I affix my signature in presence of two witnesses.
